CLAIM

We claim the ornamental design for a housing for a barrier movement operator, as shown and described.

DESCRIPTION

FIG. 1 is a perspective view of the housing for a barrier movement operator showing our new design;

FIG. 2 is a front elevational view of the housing for a barrier movement operator of FIG. 1;

FIG. 3 is a rear elevational view of the housing for a barrier movement operator of FIG. 1;

FIG. 4 is a bottom plan view of the housing for a barrier movement operator of FIG. 1;

FIG. 5 is a top plan view of the housing for a barrier movement operator of FIG. 1.

FIG. 6 is a right plan view of the housing for a barrier movement operator of FIG. 1; and,

FIG. 7 is a left plan view of the housing for a barrier movement operator of FIG. 1.
